UNITED STATES PATENT OFFICE.

PHILIP H. MONARQUE, OF NEW YORK, N. Y.

DISPLAY DEVICE.

Application filed August 28, 1924. Serial No. 734,692.

My invention relates to improvements in display devices or holders, and more particularly has reference to a suitable form of cardboard holder adapted to be folded out of a blank to display pencils or the like with suitable printed matter.

In the accompanying drawings, I have illustrated in Fig. 1 in plan view a piece of card, suitably marked or scored and punched 10 for folding and pasting to form a pencil display holder such as illustrated in Fig. 2 wherein the same is shown in perspective, parts being broken away.

Referring to said drawings, the section indicated by the reference character 3 forms the back of the device, and terminates at the bottom as indicated at 4. At the top the section 5 having suitable holes such as 6, is bent over forwardly and the next section 7 having 20 the cut-away portion 8 is then bent over downwardly as shown, the next section 9 being bent inwardly and under, the section 10 extending upwardly and the section 11 substantially horizontally and parallel with the section 5, the end section 13 bending downwardly as shown. The free end 13 is also preferably pasted or suitably secured to the section 7 as shown and the lower end of the back section 3 is likewise also preferably secured to the section 10 by paste or other suitable material.

The flaps 14, 15 are pressed outwardly from the back of the stand as shown, serving to support the same, and the horizontal flap 35 16 provided with end lugs 17 is bent down substantially at right angles to the back 3 to engage a hole, the triangular flaps 14, 15 pro-

jected as shown, thus serving to provide a proper support for the holder, the whole being stamped out of a single card as shown, 40 and the pieces stamped out of the cut-away portion 8, serving for use as tickets or for other suitable purposes, thereby salvaging practically the entire card when used. Suitable merchandise, such as pencils 18 are introduced through the upper hole 6 in the section 5 and extend downwardly through the lower holes 19 in the section 11 projecting at the top and being visible through the opening 8. Paste or other suitable fastening means is also of course preferably applied beneath the flaps 16' thereby securely holding the device as formed.

Of course it will be understood that various modifications may be made in the construction and arrangement of parts without departing from the spirit of the invention as claimed.

I claim:

A device of the class described comprising 60 a single sheet of material bent to form a rectangular main portion, a rectangular inner portion at the base thereof, holes through said portions for retaining objects to be displayed, flaps bent out of said main portion to provide support therefor, said device adapted to stand with the upper portion extending slightly rearwardly, and smaller flaps engaging said first mentioned flaps for holding same in extended position.

In testimony whereof I hereunto affix my signature.

PHILIP H. MONARQUE.
